UNITED STATES PATENT OFFICE.

LIONEL BULL, OF LIBERTYVILLE, ILLINOIS.

TEAT-CUP.

1,187,131.

Specification of Letters Patent. Patented June 13, 1916.

Application filed November 13, 1915. Serial No. 61,312.

To all whom it may concern:

Be it known that I, LIONEL BULL, a subject of the King of Great Britain, and resident of Libertyville, county of Lake, and State of Illinois, have invented certain new and useful Improvements in Teat-Cups, of which the following is a specification, and which are illustrated in the accompanying drawings, forming a part thereof.

10 The invention relates to teat cups for use in connection with milking machines; its object being to simplify and generally improve upon the construction of devices of this character.

15 The invention consists of an outer shell or casing of rigid material having an in-standing shoulder at one end, a flexible and preferably elastic tube within the casing and having its upper end inturned to form a 20 sealing flap for inclosing the cow's teat—the fold of the tube overlapping the casing shoulder and preferably inclosing a rigid ring,—and an annular nut in threaded engagement with the end of 25 the casing and binding the fold of the tube to the shoulder. Means are provided for securing the lower end of the tube within the casing, and for the attachment 30 of a suction tube, but this latter feature is without novelty.

In the drawings illustrating the invention, Figure 1 is a perspective of one form 35 of tube disconnected from the casing; Fig. 2 is a view of the expanding ring used in the tube; Fig. 3 is a perspective of a somewhat different and preferred form of tube; Fig. 4 is a longitudinal sectional view of the device; and Fig. 5 is an end view thereof.

40 The invention relates to improvements in the teat cup forming the subject of Letters Patent No. 1,144,346, issued to me June 29th, 1915.

45 The device comprises an outer shell or casing 10 of rigid material, and preferably of metal, within which is inclosed a flexible and preferably elastic tube 11, having its ends in sealed engagement with the casing, the lower end of the tube inclosing a nipple 12 to which a suction and milk-conveying

tube may be attached, and the casing being 50 also provided with a nipple 13 to which a suction tube may be attached. An annular nut 14 is in threaded engagement with the upper end of the casing 10, its instanding flange binding an outwardly projecting fold 55 of the tube against an instanding annular shoulder 15 of the casing. The tube 11 may be normally of uniform diameter from end to end and adapted to freely enter the casing past the shoulder 15. A rigid ring 16 60 is inserted within the tube for the purpose of expanding it over the shoulder 15, and the end of the tube is then turned inward to form a depending conical shaped annular flap 17. The fold 18 of the tube extends 65 over the shoulder 15, and, the nut being applied, compresses it upon the ring and upon the casing shoulder. Preferably, however, as shown in Fig. 3, the tube 19 is molded to form an instanding annular flap 20. The 70 ring 16 being inserted into the tube and forced to the base of this flap, expands the tube to the form as shown in Fig. 4. In either form the tube is rendered more durable and pliable, and a more perfect seal 75 with the casing at its upper end is secured.

The parts are easily assembled and disconnected for cleansing, in either form of construction the flap being easily outturned when the tube is freed from the casing, leaving its inner surface smooth and without creases.

I claim as my invention—

1. In a teat cup comprising, in combination, a casing of rigid material and having 85 an instanding annular shoulder at its upper end, an elastic tube within the casing and normally of less diameter than the inner edge of the shoulder, a ring within the tube and expanding it over the shoulder, and an 90 annular nut in threaded engagement with the casing and bearing upon the expanded portion of the tube.

2. In a teat cup comprising, in combination, a casing of rigid material and having 95 an instanding annular shoulder, a flexible tube within the casing and having its end inturned, the fold of the tube overlapping

the shoulder of the casing, and an annular nut engaging the end of the casing and binding the fold of the tube to the shoulder.

3. In a teat cup comprising, in combination, a casing of rigid material and having an instanding annular shoulder, a flexible tube within the casing and having its end

turned, the fold of the tube overlapping the shoulder of the casing, a rigid ring inclosed within the fold of the tube, and an annular nut engaging the end of the casing and binding the fold of the tube to the shoulder. 10

LIONEL BULL.
